lands, Calif., assignors to The Miehle Printing
Press and Manufacturing Company, Chicago,
Ill., a corporation of Illinois

Application December 1, 1933, Serial No. 700,416

20 Claims. (Cl. 101—189)

This invention relates to a printing press and, while adapted for use on various types of printing presses, it finds particular application in connection with presses of the sheet-fed, bed-and-cylinder class in which two or more single color printing units are arranged in tandem to provide a press for producing multicolor work.

In multicolor printing presses, particularly of the bed-and-cylinder class, a transfer cylinder is arranged between the impression cylinders of two adjacent printing units for the purpose of transferring the sheets from the impression cylinder of one color unit, after having received their first impression therefrom, to the impression cylinder of the other unit to receive their second color impression.

Such arrangements have the disadvantage for instance that any variation in the register which frequently develops during the printing of a job due to shrinkage or stretching of the stock and other causes, cannot be corrected without considerable loss of time, because on that type of presses such correction requires accurate and tedious readjustments of the sheet controlling means and other parts involved.

Furthermore, because of the several color impressions being applied to the sheets in quick succession, no drying time is provided between each color impression, resulting in smutting of the first impression during the transfer of the sheets from one impression cylinder to the other with the printed side of the sheets facing the transfer cylinder.

Moreover, it is impossible to observe the first impression and color setting on a sheet, because the sheet, at the time it again becomes visible to the pressman, after having been fed to the press, has received the impressions from all of the color units.

It is therefore the primary object of the present invention to eliminate the disadvantages referred to above by the provision of a press in which for the conventional transfer cylinder a novel sheet transfer and controlling means is substituted which will make it possible to observe the impression of a sheet as it comes from the first color unit, provide ample time for the ink of the first or any preceding impressions to dry before a succeeding impression is applied, as well as to readily correct any variation in the register of the impressions.

Another object of the invention is to arrange the units of such a press in a manner that the

vital operating parts thereof are rendered readily accessible to the pressman.

A further object consists in the provision of means whereby the sheets to be printed will be under positive control during their passage through the press.

Another object resides in the provision of mechanism whereby the sheets, as they approach the registering guides, will be effectively slowed down to assure accurate registering.

A still further object of the invention resides in means whereby a pressman may disconnect any one of the printing units from the power drive of the press so that makeready and other work can be performed on any disconnected unit regardless of the other units.

These and other objects set forth hereinafter are accomplished by the arrangement disclosed in the following description and illustrated by way of example in the accompanying drawings, in which:

Figure 1 is a side elevation of two single color printing units combined into a two-color printing press and embodying the features of this invention;

Figure 2 is an outline in plan view of the printing press illustrated in Figure 1, showing more particularly the arrangement of the power drive connections for the two units;

Figures 3 and 4 illustrate the relative position of the type forms of the two units during a printing cycle of the press;

Figure 5 is a plan view of the forwarding table which receives sheets from the delivery conveyor of the first unit and on which the sheets bearing the first impression are again registered before they are passed into the second unit to receive the second color impression;

Figure 20 is a section taken along line XX—XX of Figure 19.

Referring now to Figure 1, each printing unit has a frame 20, 20' respectively, which frames are rigidly held in spaced relation to each other by means of a base plate 21. The first unit A is provided with an automatic feeder 22 from which sheets of stock to be printed are fed to the impression cylinder 23 in any known conventional manner. After a sheet has received its impression from the form on the bed 24 of the first unit, the sheet is taken over by the delivery conveyor 25 which in the preferred form illustrated is of the endless chain and gripper type. This conveyor deposits the sheet bearing the first impression onto a forwarding table 26 on which the sheet will be slowed down and re-registered prior to receiving its second impression, as will be explained hereinafter in detail.

Upon having been properly registered on said forwarding table, the sheet is transferred to the impression cylinder 23' of the second unit by any convenient means, preferably, however, by a rotary or an oscillatory stop gripper mechanism, whereby the sheet is engaged while at rest in registered position on the forwarding table and transferred to the impression cylinder grippers at impression cylinder speed. After the sheet has received its second impression on the unit B, it is taken over by the delivery conveyor 25' of the second unit, and subsequently deposited onto the pile delivery 27.

By the provision of a forwarding table between adjacent printing units, in addition to the endless conveyor shown, ample time is provided for the ink of one impression to dry before a sheet receives its successive impression. The pressman may also readily observe the color setting, etc. of any impression while the sheets printed side up are on the forwarding table during their transfer from one printing unit to another.

It will also be understood that by the arrangement of accessible registering means on the forwarding table, which means may be of any conventional type, variations in the register, that might develop during printing, can be conveniently corrected with the least possible loss of time.

Preferably both units are driven by means of a line shaft drive which receives its power from a single motor, as illustrated in Figure 2. The driving motor 28 is mounted in a convenient position at the gear side of the press so that it will not interfere with the accessibility of the space provided between the two units, i. e. between the delivery end of the first unit and the feeder end of the second unit, in order that a pressman may conveniently attend to makeready or other work at that station.

The line shaft 29, which extends in both directions of the motor 28, is connected to the motor by any suitable means such as by a chain or belt drive 30 and rotation is transmitted simulta-

neously to the drive shafts 31, 31' of the two units, preferably by bevel gears 32, 33 and 32' and 33' respectively. For the purpose of disconnecting either one of the printing units from its respective drive shaft, so that makeready and other work may be performed simultaneously on each unit and independent of each other, a clutch mechanism is provided on each unit whereby a pressman may disconnect at will that particular unit on which he wishes to perform certain operations which do not require running of the press, while the other unit may remain connected to the drive and be run by another pressman for certain operations that require running of the press, such as inching. This clutch mechanism, which is illustrated in Figures 19 and 20, will be explained in detail hereinafter.

Referring to Figures 3 and 4, the diagrammatic views of the printing couples forming part of the units A, B are intended to illustrate the direction and extent of travel of the forms of the respective units during a printing cycle of the multicolor press.

The inking mechanism whereby a film of ink is applied to the type form 34, 34' respectively, may be of any conventional kind and may include a fountain and fountain roller 35, a ductor roller 36, an ink distributing drum 37, a second ductor roller 38 mounted to rotate about the axis of the drum 37 and remaining in constant contact with said drum, steel vibrator rollers 39, rider roller 40 and two or more form rollers 41.

In the unit A shown in Figure 3 the printing couple is illustrated during its printing stroke, namely during that stroke on which the impression cylinder 23 is in impression on the form 34, the form traveling and the cylinder rotating in the directions indicated by the arrows. The extent of the full travel of the bed 34 is indicated in broken lines and shows that when the form has reached its end position prior to reversing, the inner edge of the form will have passed beyond its point of contact with the cylinder. Prior to the return stroke of the form, the cylinder 23 of the unit A is tripped, i. e. raised above the form so that it will not contact therewith. The cylinder will remain in its tripped position until the beginning of the next printing stroke.

The unit B shown in the position illustrated in Figure 3 is in that position during which the impression cylinder 23' is tripped off the form 34' and the form traveling in the direction shown by the arrow receives its supply of ink from the form rollers 41'. The end position of the form 34' traveling in this direction is indicated by broken lines, in which position the right hand edge of the form will have cleared the second form roller 41'.

After the form 34' has completed its travel in the direction shown in Figure 3, the form i. e. the bed on which the form is mounted, is reversed and will then travel in the direction indicated by the arrow in Fig. 4. In that figure the impression cylinder 23' is shown as having been lowered onto the form so as to effect an impression onto the sheet carried by said cylinder. During that part of the printing cycle of the two units, the bed 34 of the unit A is on its return stroke and the impression cylinder 23 is tripped off the form and the latter receives a film of ink from the form rollers 41. During the entire printing cycle of the units A and B, the impression cylinders 23 and 23' continue to rotate in the same direction.

With this relative timing of the printing units, it will be seen that at no time will the impres-

sion cylinders of the two units be on impression simultaneously; in other words, while one cylinder is on impression during the printing of a sheet on that particular unit, the impression cylinder of the other unit will be off impression, i. e. tripped off the form. This is a feature of importance because it avoids any overload on the motor which obviously would occur if both impression cylinders were on impression simultaneously.

By reciprocating the forms of the two units, i. e. the type beds on which the forms are mounted, in opposite directions, a counterbalancing effect is produced which will absorb the stresses that would otherwise be transmitted to the structure of the press by the reciprocation of the type beds.

The forwarding table 26, a plan view of which is shown in Figure 5, has mounted thereon a series of sets of suction i. e. forwarding wheels 42, 43 and 44, preferably of the construction shown in Figures 12 to 15, which figures will be described later. The latter two sets of said wheels are rotated at a uniform speed, while the wheels 42 are given a variable speed of rotation in order to slow down a sheet prior to it reaching its registering position.

Rotation is imparted to all of said forwarding wheels from any convenient part of the press drive, preferably by means of a shaft 45 and bevel gear 46, see Figure 8, which gear extends into the drive case 47 mounted on one side of the table 26, see Figure 5.

The shafts 48 and 49 which carry the suction wheels 43 and 44 respectively, extend through the side wall or flange 50 of the forwarding table 26, and the bevel pinions 51, 52 keyed to the free ends of said shafts mesh with complementary bevel pinions 53 and 54 carried by the shaft 55, which is continually rotated at a uniform speed from the drive shaft 45, through the intermediary of the bevel pinion 56, pinion 57 and bevel pinions 58 and 59.

As indicated above, the suction wheels 42, located near the front end of the forwarding table 26, are not rotated at a uniform speed but are imparted a variable speed for the purpose of slowing down a sheet prior to it being presented to the registering guides. The mechanism whereby the variable speed is accomplished is shown in Figures 5, 6, 8, 9, and 10. The cam shaft 60 which constitutes the drive shaft for said mechanism, carries at one end a helical gear or worm wheel 61, see Figures 9 and 10, which wheel meshes with a helical gear or worm 62 provided on the continually rotating shaft 55. At the other free end of the shaft 60 is mounted a centroidal gear 63, see Figures 5 and 6, which in turn meshes with a complementary centroidal gear 64 mounted for rotation, together with a pinion 65, on a stud 66 threaded into the side of the table 26. Pinions 67 and 68, which are integral and mounted for rotation on stud 69, preferably driven into a bore in the table 26, transmit a variable rotation to the solid shaft 70 and therewith to the suction wheels 42, by means of a pinion 71 which is secured by any convenient means to the reduced free end of the solid shaft 70. The timing of the centroidal gears of course is such that the suction wheels 42 rotate at top speed at the moment when a sheet reaches them, while from then on until the leading edge of a sheet is presented to the front guides, the rotation of said wheels will be decelerated so that they will have assumed their lowest speed and thereby have sufficiently slowed down

the sheet by the time it reaches the front registering guides to assure smooth contact of its leading edge with said guides. The train of gears whereby this variable rotation of shaft 70 is produced may be covered by a guard C.

Suction is applied to the forwarding wheels 42, 43, and 44 in timed relationship and preferably controlled by the means illustrated in Figures 5 and 8 to 11.

In the housing 72 is provided a bore 73, see Figures 9 and 11, into which is threaded a nipple 74 for connection with the main air line 75, which leads to any conventional vacuum system such as a pump on the press. Air vents 76 extend from the bore 73 to the inner face 77 of said housing.

Referring now particularly to Figures 9 and 11 of the drawings, the housing 72 is provided with three bores 78 into which are driven studs 79, 80, and 81, each of which has a reduced portion 82 which projects beyond the face 77 in the housing 72 in order to provide bearing journals for the air control valve gears 83, 84, and 85. These gears are held in position on their respective journals by means of a cover plate 86 secured to the housing 72 preferably by bolts 87 and suitably spaced from the face 77 in any convenient manner so that said gears will be free to rotate between the face 77 and the plate 86. Each one of said gears functions as a valve to control the vacuum to the respective suction wheels in the forwarding table 26, and for that purpose air openings 88 are provided in said gears in such position that once during every revolution of a gear the opening 88 therein will align itself with its corresponding air vent in the housing 72. In the cover plate 86 and in alignment with said air vents 76 are tapped holes 89 into which are secured nipples 90 of air lines 91, which latter lead to the respective suction wheels in the forwarding table 26. It will be understood therefore that vacuum will only then be applied to said suction wheels when the holes 89 in the cover plate, air openings 88 in the valve gears and air vents 76 in the housing 72 are in alignment.

Said valve gears intermesh and are driven to rotate continually in one direction by a gear 92, see Figures 9 and 10, carried by the cam shaft 60 and held against rotation on the hub 93 of the worm wheel 61 by means of a pin 94 driven into said hub, the worm wheel 61 being splined to the shaft 60 by a key 95 and secured in position by a set screw 96 in said hub and bearing against said key.

The speed at which the air control valve gears 83, 84, and 85 are driven is such that for every sheet fed to the printing couple of the second unit of the press, each of said wheels will perform one complete revolution. As will be understood from the location of the air openings 88 in said wheels and indicated in Figure 9, vacuum will first be applied to the wheel 83 during that period when its air opening 88 is in alignment with its corresponding air vent 76 in the housing 72 and with its corresponding tapped hole 89 in the cover plate 86. At that time no vacuum will be applied through the air openings 88 either in wheel 84 or wheel 85. When the opening 88 in wheel 83 is about to pass beyond its corresponding air vent 76, then the opening 88 in wheel 84 will commence to move into alignment with its corresponding air vent 76 and through its air line 91 will apply vacuum to the second set 43 of the suction wheels in the forwarding table 26. By the time the vacuum to the suction wheels 43 is cut

off by the continued rotation of the valve gear 84, the opening 88 in gear 85 will have moved into alignment with its corresponding air vent 76 and thereby apply vacuum to the front suction wheels 42 in the forwarding table through the air line 91 leading thereto.

As indicated in Figure 9, the opening 88 in the wheel 85 is of an elongated shape, the purpose of which will be apparent from the following description.

The suction wheels 43 and 44 function merely to advance the sheets over the forwarding table 26, while the wheels 42, in addition to advancing the sheets over said table, act to control them during that period when the sheets are being given their front and side registering movement. In order to accomplish this, it is essential that means be provided whereby the air pressure i. e. the vacuum, to the wheels 42 can be suitably varied to accommodate stock of different weights. The preferred form of such means is illustrated in Figure 8 of the drawings and includes a by-pass tube 97, which provides a direct connection between the main air line 75 and the front suction wheels 42. The air pressure within the tube 97 is controlled by means of a pet cock 98, which together with a relief valve 99 are interposed between said tube and the main line 75.

A second relief valve 100 is mounted on the cover plate 72 and has for its purpose to establish direct communication to the atmosphere through an air port provided in said plate and located in such position that once during every revolution of the air control valve gear 85, it will come into alignment with the air opening 88 in said gear and thereby brake the vacuum to the suction wheels 42. The timing of the relief valve 100 with the opening 88 in the gear 85 being such that when the leading edge of a sheet is about one-half inch from the front registering guides of the press, the vacuum applied to the wheels 42 will be relieved for the purpose of avoiding buckling of the sheet when its leading edge reaches the front registering guides.

By the time the sheet has reached its registering position, vacuum through the valve gear 85 will have been cut off completely and the wheels 42 will thereupon be in direct communication with the main air line 75 through the auxiliary by-pass tube 97. The amount of suction applied to the sheet through said tube is controlled by the setting of the pet cock 98, only sufficient suction being required to hold the sheet down after it has been registered and to thereby prevent displacement of the sheet, also to prevent the side guides from pulling the sheet away from its front registering guides during registering movement of said side guides.

The setting of the pet cock 98 is constant for the majority of stock handled on presses of this type, but for extremely light stock for instance, or for cardboard, the volume of air pressure in the bypass tube 98 may be suitably varied.

The relief valve 99 is used for relieving the suction in the main line 75 and thereby in the suction tubes on the forwarding table when exceedingly light stock, such as tissue paper, is handled on the press. By suitable adjustment of the relief valve 99, the vacuum can be held to a minimum so that during the forwarding of such exceptionally light stock, the paper will not be sucked into the air vents of the suction wheels.

It might also be mentioned here that the vacuum at the air wheels 44 is so timed with the grippers on the delivery conveyor 25 that before

said grippers release the sheet, suction will have been applied to said wheels so that the sheet may be under positive control during its transfer from the delivery conveyor to the forwarding table 26.

In order that sheets to be registered will not be thrown out of alignment with the front registering guides during the side registering of the sheets, the front suction wheels 42, in addition to their rotary motion are imparted a lateral movement while a sheet is under their control, which movement is accomplished by means of a cam 101 mounted on the cam shaft 60, see Figure 5, a rocking lever 102 pivotally mounted on a bracket 103 secured to the side of the forwarding table and which lever at one end carries a roller 104 engaging in the cam groove 105 of the cam 101, while the other end of said lever is provided with a gear sector 106 engaging the teeth of a rack member 107 secured to the hollow shaft 108 on which the suction wheels 42 and associated parts are arranged as a unit to move therewith laterally.

In order that the wheels 42, which rotate with the shaft 70, may readily slide longitudinally of said shaft to follow the lateral movement of the shaft 108, they may be splined to the latter shaft by means of a key and key way or in any other preferred manner. During the rotation of the shaft 60 which carries the cam 101, the lever 102 will be rocked and consequently the wheels 42 will be moved laterally to and fro on the shaft 70. The lateral movement of said wheels of course occurs after suction has been cut off on the wheels 43 and 44, so that the sheet will be entirely under the control of the wheels 42. Furthermore, it will be readily understood that the suction in the wheels 42 will be timed so that during the return lateral movement of said wheels, namely during the in movement to the left as viewed in Figure 5, no suction will be applied to said wheels.

The side guide 109 which may be of any well-known conventional construction, is imparted its lateral movement preferably by means of a cam 110 pinned to the cam shaft 60, which cam engages a roller 111 mounted on a stud 112 carried by a fork 113, the stem 114 of which is pivotally connected to a bell crank lever 115, one arm of which is provided with a gear sector 116 engaging in a rack bar 117 adapted to reciprocate in the front end of the forwarding table 26 and one end of which carries the side registering guide 109.

The arrangement illustrated in Figures 5 and 7 functions to side register a sheet in a direction to the right of Figure 5. This condition, however, may be reversed simply by turning the cam 101 180° on the shaft 60 and by also mounting the side registering guides 109 at the left hand side of the rack bar 117 instead of at the right hand side as shown in Figure 5.

While any suitable type of suction wheels may be used in connection with this invention, a preferred construction is illustrated in Figures 12 to 15 inclusive, according to which each forwarding wheel unit comprises a series of discs 118, provided with perforations 119 and slots 120, one of which extends from every perforation to the periphery of the discs. Each one of said discs is secured to the shaft 70 preferably by a key 121 in order to rotate with said shaft. On the hollow stationary shaft 108 are mounted connecting brackets 122 which are secured against lateral displacement on said shaft by means of set screws 123 or the like and in such position that the bore 124 provided in each bracket will communicate with a port hole 125 in said shaft. Lateral air

vents 126 extend from the inner end of the bore 124 to each side face of the brackets 122, which vents in turn communicate with the perforations 119 in the discs 118 through ports 127 provided in sealing discs 128. These discs are secured against rotation with the shaft 70 preferably by means of a pin 129 driven into the bracket 122 and extending on both sides thereof into bores 130 provided in the discs 128. By means of these discs 10 an air tight seal is provided between the bracket 122 and the discs or wheels 118. The outer faces of said wheels are sealed by means of discs 131 loosely mounted on the shaft 70. In order to maintain constant sealing condition between the 15 bracket 122, wheels 118 and sealing discs 128 and 131, compression springs 132 are interposed between the latter discs and retention collars 133 which are adjustably mounted on the shaft 70 and are held in position by means of set screws 134, 20 whereby the tension of said springs and therewith the degree of pressure applied between said wheels and sealing discs may be suitably varied. With this arrangement it is possible to readily dismantle the entire suction wheel unit for replacement 25 of any parts or for cleaning purposes.

In order to facilitate cleaning out of the bore 124 in the brackets 122 an opening is provided to communicate with the inner end of said bore and which opening is normally sealed by means of a 30 screw 135.

It will be apparent from this disclosure that during the rotation of the shaft 70 and therewith of the wheels 118, the perforations 119 in the latter will successively come into alignment with the 35 ports 127 in the discs 128 so that suction will be applied through the corresponding slot 120 of each perforation as it passes the port 127. Each hollow shaft 108 of the different suction wheel units is connected to its respective suction controlling 40 means by way of air lines 91 as indicated in Figures 5 and 11.

Referring now to the arrangement according to which, as shown in broken lines in Figure 1, the delivery conveyor 25, together with the forwarding 45 table 26 and its associated parts, may be swung up out of their operative position so that a pressman will have convenient access between the two units for maker ready and other work, the preferred means whereby these comparatively heavy 50 parts may be manipulated with ease and safety to the pressman, are illustrated in Figures 16 to 18.

The mechanism for accomplishing this includes substantially vertically extending rack bars 136 and 137, the upper ends of which are pivotally secured in any convenient manner either to the delivery conveyor 25 or to the forwarding table 26 at each side of the press. The lower portions of 55 said rack bars are arranged to slide within guide 60 members 138 and 139, both of which are loosely carried on a shaft 140 mounted at each end in the sides of the frame 141 of the unit A. Pinions 142 and 143 are keyed to said shaft to rotate therewith and are positioned within said guide members to be in constant mesh with the racks 136 65 and 137 respectively so that, depending on the direction of rotation of shaft 140, the racks and therewith the delivery conveyor and forwarding table are moved either up or down.

70 Rotation is imparted to said shaft by any suitable means such as a worm and worm wheel drive inclosed in a housing 144 and including a worm wheel 145 keyed to the outer end of the shaft 140, and a worm 146 meshing with said wheel, see 75 Figure 17. Said worm 146 has its bearings in

brackets 147 and 148, preferably forming an integral part of the housing 144 and bolted to the frame 141 by means of bolts 149. That bearing journal of the worm 146, which is carried in the bracket 147 has an extension to which is keyed 5 a bevel pinion 150, the other bearing journal 151 of said worm is extended beyond the bracket 148 and has mounted thereon a thrust bearing 152. The inner end of a stub shaft 153 is supported by a suitable bearing in the frame 141 and has secured thereto a bevel pinion 154, which meshes with the bevel pinion 150 on the journal of the worm 146. The free end of said stub shaft extends through a bearing portion 155 provided in the housing 144 in order to carry a handle 156 10 whereby the stub shaft 153 may be rotated by engagement of a slot 157 in said handle with a pin 158 driven into the free end of said stub shaft. 15

In order to counterbalance the weight of the conveyor 25 and forwarding table 26 during their 20 up and down movement, a coil spring 159 supported by a hollow shaft or sleeve 160 is provided, which sleeve embraces the shaft 140. One end of said spring is anchored at 161 to the frame 141 of the press while the other end of said spring 25 is secured in any suitable manner to a disc 162. Said disc is rigidly mounted on the shaft 140 and acts on said spring in such a manner that when the conveyor 25 and forwarding table 26 30 are lowered, said spring will become tensioned, while during the upward movement of said parts, the power stored up in the tensioned spring will be transmitted to the racks 136 and 137 by means of the pinions 142 and 143 respectively and thereby act as a counterbalancing means for the parts 35 to be moved. It will be understood that any convenient means may be used for adjusting the tension of the spring 159.

The mechanism whereby any one of the press 40 units may be disconnected from its respective driving shaft in order to render a unit inoperative for the purpose set forth hereinabove, is illustrated in Figures 19 and 20.

The fly wheel shaft 170, which is supported in suitable bearings 171 in the press frame 20 and 45 through which the bed motion mechanism of a unit is driven, carries at its free end a fly wheel 172, while a pinion 173 is keyed to that portion of said shaft which is located between the press frame and said fly wheel. The pinion 173 meshes 50 with a pinion 174, which latter is mounted on the free end of the shaft 31 to rotate freely thereon. The hub 175 of the pinion 174 is formed with a recess 176 which extends laterally across the entire face of said hub so as to form a clutch 55 member. A complementary clutch member 177, with a projection 178 extending across the inner face thereof and adapted to engage said recess 176 in the hub 175, is splined onto the extreme end of the shaft 31 by means of a key 180, see 60 Figure 20, recessed in said clutch member 177 so that the latter may be slid longitudinally of the shaft end into and out of its operative position with relation to the pinion 174, i. e. the recess 176 in its hub 175. 65

As shown in Figure 20, a spring actuated plunger 181 having an operating knob 182, is provided in the clutch member 177, which plunger, when said member is in its operative position, engages a recess 183 formed in the shaft 31 in order to 70 prevent the projection 178 from becoming disengaged from its complementary recess in the hub 175. In the inoperative position of the clutch member 177, said plunger will engage a recess 184 also formed in the shaft 31 and thereby prevent 75

any accidental engagement of the clutch members while a pressman is attending to certain work on the respective unit.

In order to facilitate the manipulation of the member 177, a handle 185 is provided thereon which the pressman engages, after having withdrawn said plunger 182 to move said member into its required position, that is either into or out of its operative position. A pin 186 driven into the extreme end of the shaft 31 serves to retain the clutch member 177 on said shaft.

It will therefore be seen that upon disengagement of the clutch member 177 from the recess 176 in the hub 175, the pinion 174, which is mounted free on the shaft 31, will not drive the pinion 173 on shaft 170 and therefore the respective unit will be disconnected from the power drive of the press. The operator working on that particular unit, however, may if necessary turn 20 over the press by hand by rotating the fly wheel 172.

We claim:

1. In a multicolor printing press, the combination of a plurality of printing units arranged in 25 tandem, each of said units having a printing couple comprising an impression cylinder and a cooperating type bed, an endless chain gripper conveyor on one printing unit, a forwarding table associated with said conveyor to receive printed 30 sheets in timed sequence therefrom, and means on said table for controlling sheets and registering them before they are fed into an adjacent unit.

2. In a multicolor printing press, the combination of a plurality of printing units arranged for successive printing operation, each of said 35 units having a printing couple comprising an impression cylinder and a cooperating printing form carrying member, a pivoted endless chain gripper 40 conveyor on one printing unit and adapted to be moved out of its operative position, a forwarding table associated with said conveyor to move therewith and to receive printed sheets in timed sequence therefrom, and means on said 45 table for controlling sheets and registering them before they are fed into an adjacent unit.

3. In a multicolor printing press, the combination of a plurality of printing units arranged in tandem, each of said units having a printing 50 couple comprising an impression cylinder and a cooperating type bed, a delivery gripper conveyor on one printing unit, a forwarding table rigidly associated with said conveyor to receive 55 printed sheets therefrom, and means for moving said conveyor and table as a unit into and out of their operative position.

4. In a multicolor printing press, the combination of a plurality of printing units arranged in tandem, each of said units having a printing 60 couple comprising an impression cylinder and a cooperating type bed, a delivery conveyor on one printing unit and adapted to be moved out of its operative position, a forwarding table associated with said conveyor to receive printed sheets 65 therefrom and to move therewith, and means for balancing said conveyor and table during their movement out of their operative position.

5. In a multicolor printing press, the combination of a plurality of printing units arranged for successive printing operation, each of said units 70 having a printing couple comprising an impression cylinder and a cooperating printing form carrying member, a delivery conveyor on one printing unit and adapted to be moved out of its operative position, a forwarding table associated

with said conveyor to receive printed sheets therefrom and to move therewith, and means for balancing said conveyor and table during their movement out of their operative position.

6. In a multicolor printing press, the combination of a plurality of printing units arranged in tandem and each having an impression cylinder, a delivery gripper conveyor arranged to remove a printed sheet from the impression cylinder of one unit, a forwarding table associated with said conveyor to receive a sheet therefrom, suction wheels to engage and advance sheets deposited onto said table by said conveyor, and means to control the suction on said wheels so that the latter will engage a sheet before it is released by 15 said conveyor.

7. In a multicolor printing press, the combination of a plurality of printing units, each comprising an impression cylinder and a type bed co-operating therewith, a registering table associated 20 with each one of said units, and endless sheet conveying means adapted to remove a printed sheet from one of said printing units and deposit it onto the registering table associated with an adjacent unit, said sheet conveying means maintaining positive control of the sheet while transferring the same from said printing unit to said registering table.

8. In a multicolor printing press, the combination of a plurality of printing units arranged in 30 tandem and each comprising an impression cylinder and a reciprocating type bed co-operating therewith, a registering table associated with each one of said units, and endless gripper chains 35 adapted to remove a printed sheet from the impression cylinder of one of said units and deposit it onto the registering table associated with an adjacent unit.

9. In a multicolor printing press, the combination of a plurality of printing units, each comprising an impression cylinder and a type bed co-operating therewith, a registering table associated 40 with each one of said units, sheet forwarding means carried by said registering tables, and endless sheet conveying means adapted to remove a 45 printed sheet from the impression cylinder of one of said units and deposit it onto the sheet forwarding means of the registering table associated with an adjacent unit.

10. In a multicolor printing press, the combination of a plurality of printing units, each comprising an impression cylinder and a type bed co-operating therewith, a registering table associated 50 with each one of said units, sheet forwarding means carried by said registering tables, and endless gripper chains adapted to remove a printed sheet from the impression cylinder of one of said units and deposit it onto the sheet forwarding 55 means of the registering table associated with an adjacent unit.

11. In a multicolor printing press, the combination of a plurality of printing units, each comprising an impression cylinder and a type bed co-operating therewith, a registering table associated 60 with each one of said units, sheet forwarding means carried by said registering tables and comprising rotary suction members, and endless sheet conveying means adapted to remove a printed sheet from the impression cylinder of one of said units and deposit it onto the suction members of 65 the registering table associated with an adjacent unit.

12. In a multicolor printing press, the combination of a plurality of printing units, each comprising an impression cylinder and cooperating type

bed, a registering table associated with each one of said units, sheet forwarding means carried by said registering tables and comprising rotary suction members adapted to engage and slow down sheets prior to being registered, and endless sheet conveying means adapted to remove a printed sheet from the impression cylinder of one of said units and deposit it onto the suction members of the registering table associated with an adjacent unit.

13. In a multicolor printing press, the combination of a plurality of printing units, each comprising an impression cylinder and cooperating type bed, a registering table associated with each one of said units, sheet forwarding means carried by said registering tables and comprising rotary suction members adapted to slow down sheets for front register and move sheets laterally for side register, and endless sheet conveying means adapted to remove a printed sheet from the impression cylinder of one of said units and deposit it onto the suction members of the registering table associated with an adjacent unit.

14. In a multicolor printing press, the combination of a plurality of printing units, each comprising an impression cylinder and a type bed cooperating therewith, a registering table associated with each one of said units, endless sheet conveying means adapted to remove a printed sheet from one of said printing units and deposit it onto the registering table associated with an adjacent unit, and means provided by said sheet conveying means maintaining positive control of the sheet while the same is being transferred from said printing unit to said registering table, the registering table and the sheet conveying means which operate between adjacent printing units being arranged to swing as a unit out of their operative position for the purpose of providing convenient access to both type beds of said units.

15. In a multicolor printing press, the combination of a plurality of printing units, each comprising an impression cylinder and a type bed cooperating therewith, a registering table associated with each one of said units, sheet forwarding means carried by said registering tables, and endless sheet conveying means adapted to remove a printed sheet from the impression cylinder of one of said units and deposit it onto the sheet forwarding means of the registering table associated with an adjacent unit, the registering table and the sheet conveying means which operate between adjacent printing units being arranged to swing as a unit out of their operative position for the purpose of providing convenient access to both type beds of said units.

16. In a multicolor printing press, the combination of a plurality of printing units, each comprising an impression cylinder and a type bed cooperating therewith, a registering table associated with each one of said units, sheet forwarding means carried by said registering tables and comprising rotary suction members, and endless sheet conveying means adapted to remove a printed sheet from the impression cylinder of one of said units and deposit it onto the suction members of the registering table associated with

an adjacent unit, the registering table and the sheet conveying means which operate between adjacent printing units being arranged to swing as a unit out of their operative position for the purpose of providing convenient access to both type beds of said units. 5

17. In a multicolor printing press, the combination of a plurality of printing units arranged in tandem and each comprising an impression cylinder and a reciprocating type bed cooperating therewith, a registering table associated with each one of said units, and endless gripper chains adapted to remove a printed sheet from the impression cylinder of one of said units and deposit it onto the registering table associated with an adjacent unit, the registering table and the endless gripper chains which operate between adjacent printing units being arranged to swing as a unit out of their operative position for the purpose of providing convenient access to both 10 type beds of said units. 15

18. In a multicolor printing press, the combination of a plurality of printing units, each comprising an impression cylinder and a type bed cooperating therewith, a registering table associated with each one of said units, sheet forwarding means carried by said registering tables, and endless gripper chains adapted to remove a printed sheet from the impression cylinder of one of said units and deposit it onto the sheet forwarding means of the registering table associated with an adjacent unit, the registering table and the endless gripper chains which operate between adjacent printing units being arranged to swing as a unit out of their operative position for the purpose of providing convenient access to both type 20 beds of said units. 25

19. In a multicolor printing press, the combination of a plurality of printing units, each comprising an impression cylinder and a type bed cooperating therewith, a registering table associated with each one of said units, endless sheet conveying means adapted to remove a printed sheet from one of said printing units and deposit it onto the registering table associated with an adjacent unit, means provided by said sheet conveying means maintaining positive control of the sheet when the same is being transferred from said printing unit to said registering table, power driving means for said units, and means for disconnecting any one of said units from said driving 30 means. 35

20. In a multicolor printing press, the combination of a plurality of printing units, each comprising an impression cylinder and a type bed cooperating therewith, a registering table associated with each one of said units, sheet forwarding means carried by said registering tables, endless gripper chains adapted to remove a printed sheet from the impression cylinder of one of said units 40 and deposit it onto the sheet forwarding means of the registering table associated with an adjacent unit, power driving means for said units, and means for disconnecting any one of said units from said driving means. 45 50 55
